DISPENSING DEVICE

Joseph Stremel, Spokane, Wash., assignor of
two-thirds to Nellie Stremel and one-third to
Glen E. Syp, Spokane, Wash.

Application May 9, 1934, Serial No. 724,725

2 Claims. (Cl. 226—119)

My invention relates to dispensing devices and more particularly to a dispensing tube that is used in transferring liquids from one container to another. Certain objects of the invention are 5 to provide a dispensing device that does not require constant attention when used in transferring liquids from one container to another, and which is provided with novel means for allowing air to escape from the container which is being filled. Further objects are to provide a bulb that 10 is connected to the air escape means whereby overflow of the container is prevented, wherein foam rising from the filling liquid is collected, and whereby different containers are filled to an 15 equal height.

With the above and other objects in view which 20 will appear as the description proceeds, the invention consists of the novel construction, adaptation, combination and arrangement of parts hereinafter described and claimed. These objects 25 are accomplished by devices illustrated in the accompanying drawing; wherein Figure 1 is a view in side elevation showing the device installed and in readiness for transferring liquid from one container to another; and Fig. 2 is an enlarged view in central vertical section showing the device installed in a container.

Referring in detail to the drawing throughout 30 which like reference numerals indicate like parts, the device comprises a rubber or other flexible tube 5 whose receiving end is provided with an enlarged expansible mouth 6. A tapered stopper 7 is integrally and eccentrically formed on the 35 outside of said tube at a predetermined point whereby the discharge end of the tube will clear the bottom of a container 8 when the stopper is installed in its mouth 9.

The stopper 7 is provided with a vent hole 10 40 that is outside of the tube 5. An expansible rubber bulb 11 surrounds said tube and its bottom is integrally or fixedly connected to the stopper in such position as to include the vent hole 10 which hole therefore forms a passage 45 between the container 8 and the bulb 11. The top of said bulb is integrally or fixedly connected to the tube 5 and is provided with a vent hole 12 outside of said tube and which vent hole is smaller than the vent hole 10.

In the use of my device, the stopper 7 is 50 installed tightly in the mouth 9 of the empty container 8. A faucet 13 of a container (not shown), from which liquid is to be transferred into the empty container 8, is installed in the expansible mouth 6 of the tube 5 and said faucet is turned 55 on. The rising liquid in the container 8 forces the air therein upwardly and out through the vent

holes 10 and 12 in the stopper 7 and bulb 11 respectively. The vent 12, being somewhat smaller than the vent 10, a sufficient back pressure is caused within the bulb 11 to force its walls outwardly. 5

My device is particularly adapted for transferring beverages, such as beer and other foamy liquids, from one container to another. After once starting to drain liquid into the container 8 it is not necessary that it be continually watched. 10 The attendant may perform other duties during the filling process, for, if the liquid should run over, the surplus will pass slowly through the vent hole 10 into the bulb 11 thus giving the attendant ample time to shut off the faucet 13. When the 15 liquid gradually rises to the top of the container 8 the foam which forms thereon is first forced through the vent 10 and collects in the bulb 11 from which it may be drained or squeezed off 20 after removing the device from the container 8. 25

When the container 8 is full and the device has 30 been removed therefrom, the liquid will drop down slightly within the neck 9 of said container, owing to its displacement by the tube 5, and the container is then sealed by a cork. This feature 35 provides means whereby each container is filled to an equal height. It will now be apparent that I have provided means for transferring liquids from one container to another whereby constant attendance is eliminated, overflow of the container is avoided, foam is removed from the container, and each container is filled to an equal height. 40

Having thus described my invention, what I 45 claim and desire to secure by Letters Patent of the United States is:

1. A dispensing device comprising a flexible tube having an enlarged expansible mouth, a stopper formed integrally around said tube, said stopper having a vent hole therethrough, and an expansible bulb formed around said tube with its lower end fixed to the stopper and communicating with the vent hole therein, and its upper end having a vent hole therethrough. 50

2. A dispensing device comprising a flexible tube having an enlarged expansible mouth, a stopper formed integrally and eccentrically around said tube, an expansible bulb formed around said tube, the lower end of said bulb fixed to the stopper and its upper end fixed to said tube, said stopper having a vent hole extending therethrough into communication with the bulb, and said bulb having a vent hole through its upper end that is smaller than the vent hole through the stopper. 55
